APPARATUS FOR COATING FIBERS

Ernst Bleibler, Gent, Belgium

Application May 21, 1932, Serial No. 612,814
In Germany May 21, 1931

4 Claims. (Cl. 91—32)

The invention relates to a method of and apparatus for coating natural fibers, such as wool, cotton, linen, hemp and the like with cellulose in its liquid primary state and to continue the treatment as if a cellulose product were concerned, and so to impart to the fibers, in the form of single or double threads, ribbons or the like, valuable properties.

In particular, it is by means of the improved method, possible to impart to the fibers properties which they do not possess in their natural state and, on the other hand, to exploit their valuable natural properties. Thus fibers, which owing to their appearance are not adaptable for the manufacture of clothing, but possess great strength, may be made available for the purpose mentioned by imparting to them, by the improved method, all those properties which they are short of and which are valuable for the purpose in question, such as luster, dyeing capacity, waterproofness and so on.

The method of treating the fibers, according to the invention, thus opens up new fields of applications for those natural raw materials, and, for instance, materials which due to their properties were up to now unsuitable for covering walls, floors and so on may now be made useful for the purpose. On the other hand the qualities of the cellulose products are considerably improved by the treatment, in so far as the strength and durability of the natural textile materials may be imparted to them which they do not possess as a general rule. Thus spheres of utilization are opened up for cellulose products which were closed to them before.

According to this invention spreading, smoothing, stroking and the like appliances are used for distributing the cellulose in its liquid raw state around the fiber, which at the point of contact are movable transversely to the fiber or are stationary and the fiber movable transversely to them.

By the apparatus according to the invention it is possible to coat natural threads with a uniform layer of liquid cellulose, such as viscose, and to coagulate the thus obtained intermediate product without change of shape. The improved method only renders it at all possible to coat natural fibers. Natural fibers have an irregular cross-section and contain thicker and thinner portions, knots and the like, so that it is impossible to make use of the usual spinning nozzles, as their mouth is rigid and incapable of giving way, so that the fibers or threads break when thick sections pass through the nozzle and

then choke the bore. If, however, the cross-section of the passage through the nozzle or other coating device is made variable in accordance with the present invention, the resilient or elastic portions of the coating device are able to give way when forced aside by the irregularities of the fibers or threads, so that no inadmissible stresses develop in the fiber or the thread and it is at the same time possible to adapt the coating, as regards the thickness, for instance, to the variable cross-section of the thread or yarn.

According to this invention in a device for coating filaments of natural fibers with liquid cellulose derivative a strickling device may be used which comprises at least two members of rigid material for contacting the filament passing therebetween, the filament engaging portions of each of said members being so formed that the surface thereof converges gradually towards and into contact with the filament in the direction of movement of the filament. At least one of said strickling members comprises a pivoted lever which lever is arranged for movement in a path removing each point of its contacting surface away from the path of travel of the filament as soon as any thickening of the filament passes the contact point. Resilient preferably regulable means are provided for urging the lever to cause the portions which engage the filament to lightly touch the filament, and to cause them to constantly follow any unevenness of the moving filament.

In a preferred embodiment of the invention the point of contact of the pivoted lever with the filament is arranged so remote from the normal line drawn from the pivot to the path of movement of the filament, so that each point of the contacting lever surface is moved away from the path of travel of the filament.

Any of the well-known cellulose derivatives in liquid condition, such as viscose, will serve as a coating which then as soon as the fiber is saturated and coated with it passes through the spreading, or strickling or stroking device or appliance. Behind the spreading device there is provided a free length of the fiber to be treated, in order that the cellulose in its liquid raw condition is able to distribute itself uniformly around the thread after it had been forced aside by the spreading or stroking device. Immediately behind the free length, the cellulose is coagulated, either throughout or only on the surface, by the thread coated with the cellulose raw product being passed through a coagulation bath.

According to a further feature of the invention this passage through the coagulation bath is effected in such a way that the coagulation has taken place at least superficially prior to the fiber touching another solid body, such as guide rollers, thread guides or the like. In a preferred embodiment of the invention the coagulation liquid or solution is applied tangentially to the direction of travel behind the free or floating length of the fiber, as will be described in greater detail further on.

In the drawings affixed hereto and forming part of the specification the invention is illustrated as embodied in a number of constructions, partly by perspective views, partly by diagrams. It will be readily understood, however, that my invention is by no means limited to these constructions and that the scope of my invention and the ambit of my appended claims extends 20 to any construction incorporating the broad principle underlying my invention.

In the drawings:

Fig. 1 shows in vertical section and in diagrammatic fashion, a receptacle containing a cellulosic solution in conjunction with a coating, strickling or stroking device.

Fig. 2 illustrates a sectional elevation, a nozzle constructed according to this invention.

Figs. 3 and 4 show in side elevation and in plan 30 another modification of a strickling device.

Figs. 5 and 6 show in side elevation and in plan respectively, another form of the invention.

Figs. 7 and 8 show in side elevation and in plan 35 respectively, still a further form of the invention.

Figs. 9 and 10 are a side elevation and plan respectively of another form of the invention.

Figs. 11 and 12 show two examples of an arrangement of a primary bath vessel, a coagulating bath vessel and means for passing the thread 40 to be treated from one bath to the other without touching any rigid part other than the strickling device.

Referring to Fig. 1 of the drawings 11 indicates a receptacle containing the cellulose in 45 its liquid primary state, for instance in the form of viscose. The thread 13 to be coated is unwound from a reel 14, passed over a guide roller 15 through the bath 12 and issues from the bath at a strickling coating, applying or spreading device 16. Some designs of this device are, by way 50 of example, illustrated in Figs. 2 to 15 of the drawings.

Fig. 2 of the drawings illustrates in sectional elevation a nozzle the mouth portion 20 of which 55 consists of a plurality of movable sections 21. These sections may be formed by incisions or slits 22, so that, provided the nozzle is constructed of an elastic material, the sections can be bent back and give way; the sections 21 may, however, be 60 pivotally mounted or hinged at their bases as indicated at 25. The sections of the mouthpiece are then drawn together or forced against the thread by a helical spring in form of a ring 23, but are able to give way when encountering irregularities in the thread.

In the embodiments shown in side elevation in 65 Figs. 3 and 5 and in plan in Figs. 4 and 6, the spreading or stroking device consists of members 30, 31 and 32, 33 respectively having the tendency 70 to approach each other and provided with rounded faces as in Fig. 3, or oblique faces, as in Fig. 5 and thus gradually converge into a slit 35 or 36 forming a tapering outlet opening. One of these members, for instance 32 in Figs. 5 and 6, or both bodies 30, 31, as shown in Figs. 3 and 4,

are adapted to rock around pivot pins 40, and are forced against the thread 13, by means of a sliding weight 41 as in the example of construction shown in Figs. 3 and 4, or by an adjusting spring 42, 43 as illustrated in Figs. 5 and 6, but are able to swing 5 or to approach and recede under the action of irregularities in the cross-section of the thread. These members are preferably so arranged, that under normal conditions they are in stable equilibrium under the action of the retrieving forces, 10 i. e. the weights 41, spring 42, and that their deflecting motion under the influence of irregularities of the thread starts in the direction of travel of the thread or the like.

The operative faces of the strickling or coating device are preferably so designed that they gradually converge into a slit. The slit may be uniform across the entire width of the coating device, but it may also, as shown in Fig. 6, be provided with recesses 46 at the point of exit of the 20 fiber or thread. By varying the position of the sliding weight or the tension of the spring it is thus possible to adapt the mode of operation of the coating device closely to the conditions prevailing, the nature of the material, the strength 25 of the fiber or the thread, the viscosity of the cellulose in its primary state, and to control the device accordingly.

The Figs. 7 and 8 illustrate a further construction of the coating device. In this embodiment of the invention the bodies tapering into nozzles consist of two parts 50, 51 of rectangular cross-section. One part comprises a mouthpiece 52 adapted to rock around a hinge pin 53, which under the action of the spring 54 is pressed 30 against the fiber or thread 13 by means of a system of lever 55, 56 and adapts its position to the irregularities of the cross-section of the thread. In view of the viscosity of the liquid or solution used for coating, a lateral confinement is unnecessary in these coating devices; the liquid will first surround the thread with a flattened cross-section which, however, with regard to the free length of thread located behind the point of issue from the coating device, contracts into a uniformly round cross-section. This uniform application of the cellulose solution around the fiber or threads may be adjusted by suitably setting the working speed, controlling the viscosity of the cellulose solution, the pressure applied to the 40 point of exit from the coating device and so on.

It will be understood that rods, rollers, drums and the like over which the fiber is guided along a sinuous path may also serve as a spreading or stroking device.

In Figs. 9 and 10 the rollers 88, 89 are held in 55 jaw-like structures 90, 91 and 92, 93 respectively by pivotally mounted members 94, 95, one of which is adapted to rock around the hinge pin 96 fixed in the members 94. The pressure may 60 be adjusted or regulated by means of springs, or as shown in the drawings by means of the sliding weights 99.

The coating devices according to the invention are preferably constructed of an acid- and 65 base-proof material, such as a ceramic material, porcelain, glass or the like, or of a precious metal, for instance nickel or its alloys or of a core or foundation body covered or coated with a ceramic material or corrosion-proof metal. In all cases 70 the coating devices will be so constructed that they do not change the direction of travel of the fibers or the thread at all or only an inconsiderable extent. In this way it is avoided that the cellulose solution is entirely or partly stripped 75

or wiped off the thread on the deflected side and the equalization of the cellulose solution around the periphery of the thread affected thereby.

In Figs. 11 and 12 of the drawings two examples are shown which illustrate how the fiber, thread or tape passes from the primary bath of viscose, for instance, and the coating device into the further treatment baths. To start with a free or floating length of thread is provided behind the coating device or between the coating devices at 110, in order to enable the primary liquid to distribute itself uniformly around the thread. To avoid injury of the thus formed and uniformly distributed coating on the thread, the coating is according to a further feature of the invention immediately behind the free length throughout or superficially coagulated before the fiber, the thread or band comes in contact with another solid body, for instance a guide roller or thread guide or the like. For carrying out this feature of the invention the coagulation liquid is applied to the fiber or the like tangentially in the direction of travel.

In the embodiment illustrated in Fig. 11 the fiber or thread to be treated enters an annular nozzle 111 designed as mouthpiece of a vessel 112. The vessel 112 contains, for instance in an annularly shaped extension directed downwards from the vessel, for example, a store of liquid, which is fed to the nozzle under pressure through the pipe 114, a suitable pumping device 115, and pipe 117. The nozzle sprays or squirts the coagulation liquid around the thread. The coating coagulates at first only superficially, so that it becomes indifferent to contact with further solid bodies, such as guide rollers and the like. From the nozzle the coagulation liquid returns through the intermediate member 116 into the vessel 112, so that the coagulation liquid describes a closed cycle. The treated thread 110 is in the vessel 112 subjected to further treatment of the coagulation liquid and then passes, in a manner not shown in the drawings, into further finishing baths, identical with those customary in the manufacture of cellulose products. The thread is then wound on to the reel or bobbin 120.

In the modification illustrated in Fig. 12 the coagulation liquid is behind the free length or floating portion 110 applied to the fiber or thread or band in the form of a free jet.

The vessel containing the cellulose in its liquid primary state is designated 130; towards the exit side of the thread, in the direction of the coating device, the wall 131 of the vessel is inclined or oblique, so that contact with the thread issuing from the bath is avoided. The coagulation liquid 133 is contained in the vessel 134, which is fitted with a mouthpiece from which the coagulation liquid issues in a free jet 136. The coagulation liquid flowing out of the vessel is caught in a container 139 and through pipe 140, the pumping device 141 and the delivery pipe 142 pumped back into the vessel 134, so that it moves in a complete cycle. The thread is at 145 introduced into the free jet without coming in contact with any solid body, and passed through the jet for such a length of time, or the length of the jet, the dimensions of the vessel, the working speed of the thread and the coagulation liquid and the composition of the latter so proportioned, that the thread passes over the guide rollers 148, 149 then only when it is throughout or at least on the surface sufficiently coagulated, so that the risk of an injury to the coating no longer arises.

From the coagulation bath the thread passes through further treatment baths, drying apparatus and the like, which correspond with the customary equipment in the manufacture of cellulose products, in particular in the artificial silk or rayon industry. The treatment baths may like the primary bath be supplied to the thread tangentially to the direction of travel, in the manner described above, for instance by means of a ring-shaped nozzle or as free jet, should this be found suitable or advantageous.

For the subsequent treatment the fiber, thread or ribbon may, as in the known process, be passed from bath to bath, or to the successive apparatus in a continuous manner across a system of rollers and finally after drying be wound up on the winding reel or bobbin 120, or the finishing treatment may be carried out stepwise in separate operations, according to the prevailing conditions and the products to be obtained.

Various changes and modifications may be made without departing from the spirit of my invention and I desire therefore, that the appended claims should be construed in the light of prior knowledge.

I claim as my invention:—

1. In a device for coating filaments of natural fibers with liquid cellulose derivatives, a plurality of members formed of rigid material and having an edge-like strickling surface adapted to make contact with the fiber to be coated, said members comprising resiliently supported movable levers arranged in a circle around the thread under treatment.

2. In a device for coating filaments of natural fibers with liquid cellulose derivatives, a strickling device comprising at least two members of rigid material for contacting a filament passing therebetween, the filament engaging portions of each of said members being so formed that the surface thereof converges gradually toward and into contact with the filament in the direction of movement of the filament, at least one of said members comprising a pivoted lever, the point of contact with the filament being beyond the pivot axis of the lever in the direction of movement of the filament, whereby said lever is movable for removing each point of its contacting surface from the path of the filament upon any thickening of the filament passing the contact point, and regulable resilient means for urging said lever to cause filament engaging portions to lightly touch the filament and for causing them to constantly follow unevenness of the moving filament.

3. In a device for coating filaments of natural fibers with liquid cellulose derivatives, a strickling device comprising at least two individual members of rigid material and resilient means for urging said members against said filament under a light touch, at least one of said members being arranged for movement relative to the other in a path removing each point of its filament contacting surface from the path of the filament upon any thickening of the filament passing the contact point, whereby the filament contacting surfaces of the members are adapted to constantly follow unevenness of the moving filament with a substantially constant contact touch, a bath of liquid coating material disposed at a distance below said strickling device, a bath of liquid coagulating material disposed at a distance above said strickling device, means associated with said coagulating device for freely introduc-

ing the filament into the coagulating bath from below, there being no rigid parts in the path of filament between the upper level of the coating bath and the lower level of the coagulating bath, 5 said strickling device excepted.

4. In a device for coating filaments of natural fibers with liquid cellulose derivatives, a strickling device comprising at least two members of rigid material for contacting a filament passing there- 10 between, the filament engaging portions of each of said members being so formed that the surface thereof converges gradually toward and into contact with the filament in the direction

of movement of the filament, at least one of said members comprising a pivoted lever, the point of contact with the filament being offset substantially from the pivot axis of the lever in the line of movement of the filament, whereby said lever 5 is movable for removing each point of its contacting surface from the path of the filament upon any thickening of the filament passing the contact point, and means for urging said lever to cause filament engaging portions to lightly touch 10 the filament and for causing them to constantly follow unevenness of the moving filament.

ERNST BLEIBLER.
